Inventor:
Johann Alexander,
by Alexander S. Lunt,
His Attorney.

UNITED STATES PATENT OFFICE.

JOHANN ALEXANDER, OF ZEHLENDORF, BERLIN, GERMANY, ASSIGNOR TO GENERAL ELECTRIC COMPANY, A CORPORATION OF NEW YORK.

MERCURY RECTIFIER

Application filed September 18, 1925, Serial No. 57,244, and in Germany October 8, 1924.

My invention relates to the temperature control of mercury rectifiers, and has for its principal object the provision of an arrangement whereby the cooling fluid discharged 5 from a loaded rectifier is utilized to maintain an idle rectifier in condition for assuming load without delay.

It is well known that a cold mercury rectifier cannot be relied upon to assume load 10 without delay for the reason that short circuits are likely to be formed between its anodes. An idle rectifier is not therefore a real reserve or stand-by for one which is working. On the contrary, it is often 15 necessary carefully to heat the idle rectifier by means of low tension current before it is put into service. In accordance with my invention this difficulty is avoided by utilizing the cooling medium discharged from a 20 loaded rectifier to maintain an idle rectifier at a temperature which prevents the formation of undesirable arcs when its operation is initiated.

My invention will be better understood 25 from the following description when considered in connection with the accompanying drawings and its scope will be pointed out in the appended claims.

Referring to the drawings, Fig. 1 shows 30 an arrangement wherein my invention has been embodied; and Fig. 2 shows a modification thereof.

Fig. 1 shows a rectifier 1 arranged to have its temperature controlled by a medium 35 which is supplied to its cooling jacket through pipe 2 and valves 3 and 4, and is discharged therefrom to pipe 5 either through valve 6 or through valve 7, the cooling jacket of rectifier 8 and a valve 9. 40 Cooling medium may also be supplied from the pipe 2 through valve 10 directly to the cooling jacket of rectifier 8 and may be discharged therefrom to pipe 5 either through valve 9 or through valves 11 and 45 4, the cooling jacket of rectifier 1 and valve 6.

With the valves 3, 4, 7 and 9 open, the valves 10, 11 and 6 closed and the rectifier 1 operating, it is thus possible to utilize the 50 heated medium discharged from the cooling jacket of rectifier 1 to heat the rectifier 8 when it is idle. Likewise when the rectifier 8 is working and the rectifier 1 is idle, the heated medium discharged from the cooling 55 jacket of rectifier 8 may be utilized to heat

the rectifier 1 by opening valves 10, 11, 4 and 6 and closing valves 3, 7 and 9.

Fig. 2 shows a rectifier 12 to the cooling jacket of which a fluid is supplied from either a pipe 13 or a pipe 14 through a two-way valve 15 and from which this medium is discharged either to pipe 16 through valve 17 or to pipe 18 through a valve 19; a rectifier 20 to the cooling jacket of which a fluid is supplied from either pipe 13 or 14 through 30 a two-way valve and from which this fluid is discharged either to pipe 16 through valve 22 or to pipe 18 through a valve 23; and a rectifier 24 to the cooling jacket of which a fluid is supplied from either pipe 13 or 14 through 35 a two-way valve 25 and from which this fluid is discharged either to pipe 16 through valve 26 or to valve 18 through pipe 27. It will be observed that the pipe 13 is connected to a storage tank 28 and that 40 a pump 29 is connected between the collection or discharge pipe 18 for transmitting fluid therefrom to the tank.

With these connections, fluid discharged 45 from the cooling jackets of rectifiers 12 and 20, for example, may be pumped from the pipe 18 to the tank 28 and discharged therefrom through pipe 13, two-way valve 25, the cooling jacket of rectifier 24 and discharge pipe 16, so much of the heated fluid 50 as is not required to maintain the rectifier 24 at the proper temperature being discharged directly from the cooling jackets of rectifiers 12 and 20 through valves 17 and 22 respectively.

The embodiments of the invention illustrated and described herein have been selected for the purpose of clearly setting forth the principles involved. It will be apparent, however, that the invention is susceptible of being further modified to meet the different conditions encountered in its use and I therefore aim to cover by the appended claims all modifications within the true spirit and scope of my invention.

What I claim as new and desire to secure by Letters Patent of the United States is:—

1. The method of controlling the temperature of loaded and unloaded mercury rectifiers which consists in utilizing the heat 105 produced by operation of the loaded rectifier to maintain the unloaded rectifier at a temperature permitting it to be put into operation without delay.

2. The method of controlling the temper-

- ature of loaded and unloaded rectifiers provided with cooling jackets which consists in supplying a fluid to the cooling jacket of the loaded rectifier, and transmitting said fluid 5 therefrom through the cooling jacket of the unloaded rectifier.
3. The combination of loaded and unloaded rectifiers provided with cooling jackets, means for transmitting a cooling 10 medium to the cooling jacket of the loaded rectifier, and means for transmitting said

medium therefrom to the cooling jacket of the unloaded rectifier.

4. The combination of a pair of rectifiers each provided with a cooling jacket, means 15 for transmitting a cooling medium to said jackets, and means for causing said cooling medium to be transmitted through either of said jackets to the other of said jackets.

In witness whereof, I have hereunto set 20 my hand this 29th day of August, 1925.

JOHANN ALEXANDER.
